UNITED STATES PATENT OFFICE.

REUBEN E. BECKLEY, OF COALINGA, CALIFORNIA.

OIL AND GAS SEPARATOR.

1,127,722.

Specification of Letters Patent.

Patented Feb. 9, 1915.

Application filed August 12, 1914. Serial No. 856,470.

To all whom it may concern:

Be it known that I, REUBEN E. BECKLEY, a citizen of the United States, residing at Coalinga, in the county of Fresno, State of California, have invented certain new and useful Improvements in Oil and Gas Separators; and I do hereby declare the following to be a full, clear, and exact description of the invention, such as will enable others skilled in the art to which it appertains to make and use the same.

This invention relates to improvements in separators, and particularly to devices of this character for separating oil from gas as it is drawn from the well.

The principal object of the invention is to provide a valve which will be operated solely by the weight of the oil.

Another object is to provide a device of this character which is simple in construction, effective in operation and which can be installed at a comparatively low cost.

Other objects and advantages will be apparent from the following description, when taken in connection with the accompanying drawings.

In the drawings: Figure 1 is an elevation of my separating device. Fig. 2 is a vertical longitudinal sectional view. Fig. 3 is a top plan view.

The crude oil which issues from an oil well contains a large amount of natural gas, which is valuable for lighting, heating and motive power purposes. Heretofore devices have been used which included a receptacle into which the oil is discharged, the oil being the heavier part falling to the bottom while the gas escaped to the upper part of the receptacle from which it flowed through suitable conduits. A counterbalanced valve was disposed in the bottom of the receptacle and when the oil reached a level sufficient to overbalance the valve, the valve opened and the oil flowed therefrom until such time as the counterweight of the valve closed it. In such a device, a large amount of gas remained in the oil which flowed from the valve. It is the particular object of the present invention to obviate the difficulty and to permit the oil to actuate the valve without interference by the pressure of gas.

To accomplish this result, I provide a suitable closed receptacle 10 which has an inclined bottom 11 provided with a valve 12 closing a port 13 in the center of the bottom. This valve is disposed outside of the re-

ceptacle and is pivotally connected to one end of a lever 14, pivotally supported on one of the supporting legs 15 of the receptacle and carrying a counterbalancing weight 16 on the opposite end. This weight is arranged to be moved along the lever according to the amount of oil it is desired to permit to accumulate in the receptacle before the valve can open. Within the receptacle and just above the port 13 is a guide 17 and secured to the upper side of the valve is a rod 18 slidably disposed in the guide and extending vertically through the receptacle and through an opening 19 in the top of the receptacle. Secured to the upper end of this rod and clamped between the plates 20 is a flexible diaphragm 21 the periphery of which is secured to the marginal wall of the opening 19 by a suitable packing 22. The portion of the rod which passes through the plates 20 is threaded and provided with the adjusting nuts 23 above and below the plates so that the rod can be raised and lowered to adjust the position of the diaphragm with respect to the valve. In the upper portion of the receptacle are arranged a plurality of horizontal baffle plates 24 and extending from the top of the receptacle is a gas conduit 25. Leading to the side of the upper portion of the receptacle is a conduit 26 which is adapted to convey oil from the well to the receptacle.

As the oil flows into the receptacle from the pipe or conduit 26, it falls to the bottom and the level gradually rises as the oil continues to pour thereinto. The gas in the oil will escape and rise above the oil, flowing out through the conduit 25. The pressure of the gas being the same in all directions will exert equal pressure against the diaphragm and the oil which presses against the valve at the bottom thus having no effect on the opening of the valve and any gas pressure can be carried without adjustment of any part. The gas in the meantime is issuing through the conduit 25. When the oil reaches a predetermined level, the weight 16 will be overbalanced, the valve is opened and the oil permitted to flow from the receptacle. This oil is received in suitable vessels (not shown).

While I have shown a diaphragm at the upper end of the rod, I wish it understood that other similarly operating devices may be substituted therefor, as for instance, a piston and cylinder.

What is claimed is:

An oil and gas separator comprising a receptacle, a counterbalanced valve in the lower part of the receptacle, the top of the receptacle being formed with an opening, a diaphragm secured across the opening, a vertical rod connected to the valve and to the diaphragm and extending vertically through the receptacle, means for conveying oil to the receptacle, means for conveying

gas from the upper part of the receptacle and baffles arranged in the upper portion of the receptacle.

In testimony whereof I affix my signature, in the presence of two witnesses.

REUBEN E. BECKLEY.
